UNITED STATES PATENT OFFICE.

EMMA SCHELLER, OF LONG ISLAND CITY, NEW YORK.

WINDOW SCREEN.

Application filed August 17, 1926. Serial No. 129,762.

This invention relates to new and useful improvements in window screens of the rolling type and has for its primary object to provide a screen construction that is attached to the lower frame bar, the lower window sash at one end and arranged within a housing at its opposite end and being of such a construction that when the window is raised the screen will be extended from the housing and that when the window is lowered the screen will automatically move into the housing.

One of the main features of the present invention resides in the provision of means for causing the screen material to automatically wind within a casing as the window is lowered and this without the provision of the usual spring roller now depended upon in the operation of rolling screens of this character.

A further and important feature of the invention is to provide guide means for the side edges of the window screen so as to overcome any buckling of the screen while being raised or lowered, said guide means being further provided for covering a slot in the top side of the screen casing when the window is lowered or when the screen is not desired for use.

Other objects will become apparent as the nature of the invention is better understood the same comprising the novel form, combination, and arrangement of parts hereinafter more fully described, shown in the accompanying drawing and claimed.

In the drawings wherein like numerals indicate like parts:

Figure 1 is a fragmentary view in side elevation of a building window equipped with my novel screen construction which is fragmentarily disclosed in extended position.

Figure 2 is a detail vertical section thereof.

Figure 3 is a fragmentary longitudinal section for disclosing the screen casing in top plan and the screen guide means in cross section.

Figure 4 is an enlarged detail longitudinal fragmentary section of the screen casing, and

Figure 5 is a fragmentary top plan view thereof.

Now having particular reference to the drawings, there is disclosed in Figures 1, 2 and 3, a window construction that constitutes the provision of a frame A together

with a pair of conventional sliding sashes, the lower one of which is disclosed and designated by the reference character B. The present invention consists of a metallic casing 5 of heavy metal, and of circular shape in formation. This casing consists of a pair of telescopic sections 6 and 7 in order that the length of the same may be increased or diminished at will. Formed or arranged upon each of the sections at the bottom side thereof is a suitable bracket 8 that is constructed for flush engagement with the sill C of the window to permit of the attachment of the casing to the sill by reason of bolts or screws 9.

Rearwardly of its center, said casing is formed at its top side with a longitudinal slot 10, while at opposite ends of the section directly above the slot are vertical lugs 11—11 to which are pivotally secured the lower ends of L-shaped guide bars 12—12 of a length substantially equivalent to the length of the respective sections of the casing 5.

The invention further consists of a pair of screen strips 13—13 of a width substantially equivalent to the length of each of the casing sections and of any predetermined length. The inner edge of these screen strips are arranged in overlapping relation as clearly disclosed in both Figures 1 and 4.

Rigidly attached to the opposite longitudinal edges of the screen strips 13—13 are reinforcing strips 14 of spring metal that is normally of coil formation.

In actual practice the casing 5 is first anchored to the sill of the window after which the guide bars 12—12 are raised vertically into contact with the inner surfaces of the side bars of the window frame A, and inwardly of the sash B. The outer ends of the screen strips 13—13 are then attached to the lower bar of the sash frame in any desirable manner. Obviously when the sash is raised, the screen strips will be drawn from the casing to cover the opening beneath the sash. By reason of the spring strips 14 of normally coil formation, the screen strips will be drawn into the casing and be rolled therein when the sash is lowered.

It will thus be seen that I have provided a highly novel, simple and efficient screen construction for windows that is well adapted for all the purposes heretofore designated and even though I have herein shown and described the invention as consisting of cor-

tain detail structural elements it is nevertheless to be understood that some changes may be made therein without effecting the spirit and scope of the appended claim.

5 Having thus described the invention, what I claim as new and desire to secure by Letters Patent is:—

In a screen construction for windows, a hollow casing constructed for disposition upon the window sill, said casing being formed at its top side with a longitudinal slot, a predetermined length of screen material, reinforcing strips extending along the

opposite longitudinal edges of the screen material, said reinforcing strips being of spring metal and of normally coiled formation so as to normally wind the screen material in coil formation within the casing, the outer end of the screen material being attached to the lower portion of the adjacent sliding window sash in order that when the sash is raised, said screen material will be withdrawn from the casing through the longitudinal slot.

In testimony whereof I affix my signature.

EMMA SCHELLER.
